WASHING MACHINE

Sidney S. Holland, Sandusky, Ohio, assignor to
 The Apex Electrical Manufacturing Company,
 Cleveland, Ohio, a corporation of Ohio

Application March 7, 1938, Serial No. 194,308

5 Claims. (Cl. 248—13)

This invention relates to washing machines and more particularly to an improved means and method of mounting a power unit on a washing machine.

5 Heretofore washing machine manufacturers have endeavored to provide their dealers with one line of washing machines having an electric motor power unit for those customers accessible to electric power and a second line of washing machines provided with a combustion engine power unit for the use of their rural customers or customers desiring this type of motive power. In order that the dealer would be in position to furnish his customers with either a gas engine 10 or an electric motor driven machine in each of the various styles of washing machines, it has been necessary for the dealer, under the practice above outlined, to stock and display a complete line of gas engine driven models and a complete 15 line of electric motor driven models. As will be understood by those familiar with the art, the two models distinguish from each other mainly in the power unit and the mounting therefor.

To obviate the necessity for each dealer stock- 25 ing two complete lines of appliances and to render his inventory more flexible, it is among the objects of this invention to provide a washing machine and a power unit support therefor in which each washing machine is adapted to alternatively receive either a gas engine power unit or an elec- 30 tric motor power unit. More specifically it is among the objects of my invention to provide a power unit support which may be easily and quickly removed from or attached to a washing 35 machine tub support structure and in which the power unit support may carry either an electric motor or a gas engine.

It is a further object of my invention to pro- 40 vide a power unit support in the form of a metal band having a diameter less than the diameter of the washing machine support structure, whereby the band and its power unit may be arranged within the washing machine support- 45 ing structure or casing and secured thereto in operative position.

It is also an object of my invention to provide a washing machine power unit support in the form of a band having chordal struts in which the band is secured to the tub supporting structure 50 of the washing machine and the chordal struts carry the power unit.

It is a further object of my invention to pro- 55 vide a washing machine having tub supporting elements with a power unit support which will function not only to operatively support a power

unit but which will also serve to tie the tub supporting elements to each other and render more sturdy the entire assembly.

It is also an object of my invention to provide 5 a washing machine in accordance with the preceding objects in which the power unit is mounted in the structure in a manner whereby it is electrically insulated and cushioned with respect to noise and vibration from the rest of the washing machine structure.

Further objects and advantages relating to efficiency in construction and economies in manufacture will appear from the following description and the appended drawing in which:

Figure 1 is a perspective view of a washing machine having a power unit support constructed in accordance with my invention;

Figure 2 is a perspective view of a power unit support made according to my invention, pro- 20 vided with a gas engine power unit;

Figure 3 is a perspective view of a power unit support made according to my invention provided with an electric motor;

Figure 4 is an enlarged sectional view with 25 parts broken away showing the mounting of the power unit support ring on the washing machine;

Figure 5 is a sectional view with parts broken away showing a modified method of mounting a power unit support upon the washing ma- 30 chine;

Figure 6 is a sectional view taken along the line 6—6 of Figure 2, showing the cushion mount- 35 ing of the power unit;

Figure 7 is a plan view of a modified form of power unit support band.

To attain the objects outlined above and to avoid the economic disadvantages associated with the provision of two complete lines of washing machines, I have provided a washing machine 40 6, having a leg supporting structure 7, which carries a power unit support identified generally as at 10. It will become apparent as the description proceeds that the specific details of the washing machine 6 and the tub supporting struc- 45 ture or casing form no essential part of the present invention and are included herein to facilitate an understanding of the invention. In this connection it is pointed out that the washing machine may include a closed casing or cabinet 50 and that the gearing and power unit for the washing machine may be arranged either above or below the tub in said casing without departing from the teachings of my invention. The agi- 55 tator and wringer drive gearing, not shown, may

be of any conventional type provided with a belt-driven pulley.

For the purposes of illustration the washing machine 6 includes tub supporting legs 7 having a channel cross-section with the web portions thereof near their lower ends, apertured to receive fasteners 8 of a power unit assembly. Preferably the power unit assembly includes a support in the shape of a ring or band 14 made of strap iron. The band 14 may be formed from a single length of strap iron with its free ends overlapped and secured to each other as in Figure 2, or the band may comprise a unitary solid ring such as shown in Figure 3.

15 The band or ring element 14, is proportioned with respect to the diameter of the circle defined by the supporting legs 7 so that the band 14 may be arranged therein as shown in Figure 1. Although certain supporting structures may permit the securing of the band 14 directly to the washing machine, I prefer to employ the hangers 11 which are adapted to extend within the channel of the legs 7. Preferably the hangers 11 are secured to the ring 14 by means of a rivet or the like 15, and the ring and hanger are cushioned with respect to each other by a rubber grommet 16 and washer 17. A metal washer 18 bears against the washer 17 and this assembly prevents the transmission of power unit noise and vibration to the supporting structure of the washing machine. It will be appreciated by those skilled in the art that in certain installations such as for instance where a gas engine is used, the exhaust of the engine and other noises may permit the elimination of the cushioning elements 16-17 and that where desired the hangers may be riveted or otherwise secured directly to the band 14, somewhat as illustrated in Figure 5.

40 To secure the power unit such as for instance the gas engine 21 of Figure 2, within the band 14, chordal struts 22 and 23 are arranged within the band and have their ends secured to the inner periphery thereof. The chordal struts are spaced from each other a distance corresponding substantially to the width of the base of the engine 21 and J-bolts 24 are arranged to project upwardly from the chordal struts through the base of the engine 21. To provide a quiet and more or less resilient mounting for the engine, the chordal struts are wrapped in the region of the J-bolts 24 with a rubber or fiber cushion material such as 25 (see Figure 6). The gas engine 21 is provided with a pulley 26 having a V-belt groove therein and a belt running from this pulley may be arranged to drive a similarly grooved pulley on the washing machine gear mechanism (not shown).

It will be observed that the J-bolt mounting of 60 the engine upon the chordal struts 22 and 23 will permit the engine to be moved along the struts in a manner to adjust the tension in the drive belt and that the power unit may be correctly placed on the struts at the factory so as to insure efficient operation when in place in the machine.

65 The electric motor type power unit as shown in Figure 3 corresponds to the device of Figure 2 in that it is provided with hangers 11 and the diameter of the band or ring is such as will permit its mounting in the leg structure. The base of the electric motor 12 is preferably cushioned with respect to the chordal struts 22 and 23 and is provided with a pulley 27 having a V-groove to receive a belt, arranged between the motor and the gearing mechanism of the washing machine.

From the foregoing description it will be understood that the gas engine with its supporting ring structure and the electric motor with its supporting ring structure may be carried by the dealers as package units. Upon the customer having selected the type or model of washing machine tub structure desired and having indicated to the dealer his preference as to power unit, the dealer merely attaches the appropriate driving unit by means of the four bolts 8.

An alternative form of mounting for the power unit support is illustrated in Figure 5. In this type of mounting the hanger 11a extends laterally from the ring or band 14 and is apertured as at 30 to receive the stem of the caster 9. It will be observed that the weight of the washing machine is exerted through the legs 7 upon the upper surface of the hanger 11a and thus serves to hold the power unit supporting ring in position. This method of mounting the power unit in the washing machine obviates the necessity for removing any bolts or other detachable fastenings.

Although in the preferred embodiments of my invention I have shown the ring or band 14 as being circular in shape, certain installations may be suited to the use of a band non-circular or octagonal in shape such as I have shown in Figure 7. The band 33 of Figure 7 is preferably provided at four spaced points with hangers 11 as in the preferred embodiment and such hangers are secured to relatively short flat sides of the octagon. Spaced struts 31 and 32 are arranged between opposed flat sides of the octagon and said struts support the power unit in the manner heretofore described in detail in connection with the descriptions of Figures 2 and 3.

In the support of Figure 7, as well as in all other embodiments of my invention, it will be observed that the ring itself and the struts extending transversely of the ring are made of 40 strap iron, with its width or flat side arranged in a vertical plane. This disposition of the iron going into the supporting structure places the members in their most efficient load-bearing position.

It will also be observed that the power unit supporting structure is constructed and arranged in a manner which effectively ties the lower ends of the supporting legs 7 to each other. In other words, the chordal struts 22-23 and the ring 14 are subjected as beams to the load of the power unit and at the same time are subjected to tension loads in tying the supporting legs 7 to each other. Due to the construction and arrangement which I have provided for supporting the power unit and tying the legs of the washing machine to each other, it is possible to accomplish both of said functions in a more efficient and economical manner than said functions have heretofore been effected in this art.

Although I have disclosed several embodiments of my invention in considerable detail, it will be appreciated that those skilled in the art may effect modifications or changes therein without departing from the scope of the invention as defined in the following claims.

I claim:

1. A power unit support for a washing machine having depending legs, said support comprising a circular band of strap iron, a plurality of strap iron struts arranged transversely of said ring with the ends of said struts secured to the ring, a power unit having a base arranged on said struts, a plurality of J-bolts with their hooked ends disposed about the lower edge of said struts

and their upper ends projecting through apertures in said power unit base, whereby said power unit may be clamped in adjusted position along said struts and a plurality of spaced hangers 5 interposed between said legs and said band to maintain the support in operative position.

2. A power unit support for a washing machine having a tub with depending legs, said support comprising a circular ring of strap iron, a plurality 10 of strap iron struts arranged transversely of said inner face of said ring with the ends of said struts secured to the ring, a power unit having a base engaging said struts, a plurality of fastening devices arranged about the lower edge 15 of said struts and through said power unit base, whereby said power unit may be clamped in adjusted position along said struts, and a plurality of spaced hangers secured to said ring and to 20 said tub supporting leg structure.

3. A power unit support for washing machine having a tub support comprising a strap iron ring having its greatest dimension less than the greatest dimension of the tub support so as to be received therein, a power unit supported within 25 said ring and a plurality of spaced hangers secured to said ring and extending outwardly therefrom, means to detachably mount the outer ends of said hangers on said washing machine tub support, the attachment of said hangers to said ring including an insulating cushion device to 30 dampen the shock and noise of the power unit

with respect to the washing machine and its leg supporting structure.

4. A washing machine having a tub and a supporting structure depending therefrom, a plurality of casters for said supporting structure 5 having stems extending upwardly therefrom and received within said supporting structure, a power unit support for said washing machine comprising a member proportioned to fit within said tub supporting structure provided with hangers extending outwardly from the periphery thereof, each of said hangers on their outer end having an aperture adapted to receive the stem of said 10 caster prior to its insertion within the washing machine supporting structure, whereby the power 15 unit and its support are secured in operative position.

5. A washing machine comprising a tub with depending spaced legs, a power unit support detachably secured to said legs comprising a strap 20 iron ring having hangers arranged in number and in spacing to correspond to said supporting legs and secured to said legs, a pair of spaced strap iron chordal struts in said ring with their ends secured to the inner face thereof, a power 25 unit having a base supported by said chordal struts, resilient cushion members interposed between said struts and said base, and fastening means engaging said cushion members and said base to resiliently mount said power unit in its 30 operative position.

CERTIFICATE OF CORRECTION.

Patent No. 2,224,348.

December 10, 1940.

SIDNEY S. HOLLAND.

It is hereby certified that error appears in the printed specification of the above numbered patent requiring correction as follows: Page 3, first column, line 11, claim 2, strike out the words "inner face of said" and insert the same before "ring" in line 12, same claim; and that the said Letters Patent should be read with this correction therein that the same may conform to the record of the case in the Patent Office.

Signed and sealed this 8th day of April, A. D. 1941.

(Seal)

Henry Van Arsdale,
Acting Commissioner of Patents.
